RADIO APPARATUS

Charles William Hicks, Washington, D. C., assignor, by mesne assignments, to Bendix Radio Corporation, New York, N. Y., a corporation of Delaware

Original application July 12, 1935, Serial No. 31,084. Divided and this application January 18, 1936, Serial No. 59,771

7 Claims. (Cl. 250—11)

This application is a division of my copending application Serial No. 31,084, filed July 12, 1935.

This invention relates to radio apparatus generally. More particularly, this invention relates to radio receiving apparatus adapted for obtaining bearings, determining direction, courses, positions, and the like with respect to one or more transmitting stations.

An object of this invention is to provide a circuit arrangement for controlling the reception of a conventional radio receiver and for permitting uni-directional, bilateral directional, and for omni-directional reception over said radio receiver.

Another object of this invention is to provide an attachment for a conventional radio receiver whereby the directional receiving characteristics of said radio receiver may be changed at will.

Still another object of this invention is to provide an indicator arrangement for a directional antenna employing a rotatable scale and an adjustable mask adapted to be adjusted over portions of the scale when said directional antenna is being used for determining direction of signaling stations with respect thereto.

A further object of this invention is to provide a scale rotatable with a rotatable directional antenna and a mask for said scale, said mask being adjustable to cover a portion of the scale for the purpose of assisting the operator in using the directional antenna in making signal direction observations.

Other and further objects of this invention will be apparent to those skilled in the art to which it relates, from the following specification and the claims.

In accordance with this invention I provide a circuit arrangement which employs a dual type tube, having a pair of input circuits, one of which is connected to a directional antenna and the other of which is connected to a substantially non-directional antenna. I also provide means to the input or output circuits of each of the sections of the dual tube for controlling the amplifying characteristics thereof and for blocking either one of these sections at will so that signal energy from either the directional antenna or non-directional antenna or from both antennas may be impressed through said dual tube upon an amplifying and/or detecting circuit of a radio receiver.

I have shown the antenna coupling circuit, including the dual tube as a separate unit attachable to any conventional radio signal receiver, however, it is apparent that this coupling circuit

may be incorporated into the receiver and employed as the first stage radio frequency amplifier or detector of said receiver. It is, of course, also obvious that the tubes need have no amplifying characteristics but may act merely as a coupling device. In practice, it is generally desirable to reduce the intensity of the signal component impressed upon the tube from the non-directional antenna and increase the intensity of the signal component impressed upon the other tube from the directional antenna in order to balance the maximum signal intensities derived from both antennas. For this purpose one of the tubes, that is the section connected to the directional antenna is controlled by proper bias potentials to act as a relatively efficient amplifier, while the other tube is adjusted to act more or less as an inefficient amplifier or coupling unit. The signal intensities derived from the directional and non-directional antennas are thus conveniently equalized.

The signal components obtained from the directional and non-directional antennas are impressed upon a common circuit in the output circuits of the tubes and the resultant is a substantially uni-directional signal characteristic.

It is, of course, possible to amplify the outputs of the two tubes separately before impressing the signal components therefrom on a common circuit and likewise it is also possible to use a dual type tube having two triode sections instead of separate tubes in separate envelopes, as such dual tubes are well known in the art.

The operation of this invention will be more clearly understood from the following detailed description and the drawings in which, briefly, Fig. 1 illustrates a schematic diagram of connections of an embodiment of this invention; Figs. 2 and 3 illustrate the manual controls and cabinet for housing the apparatus connected in accordance with the diagram of Fig. 1; Fig. 4 is a sectional view along the line 4—4 of Fig. 2; Fig. 5 is a sectional view along line 5—5 of Fig. 2; Fig. 6 is a sectional view along the line 6—6 of Fig. 4; Fig. 7 is a sectional view along the line 7—7 of Fig. 5 and Figs. 8 and 9 are exploded views of the scale and mask. Referring to Fig. 1 in detail, reference numeral 1 designates a metal cabinet or shield for housing the vacuum tubes 3 and 4, each employing a cathode, grid or control electrode and an anode. A heater filament such as 36 is used to heat the cathodes of both of these tubes 3 and 4. The grid electrode of tube 3 is connected to the connector or slip ring 7 of the loop antenna 5 through a suitable brush or simi-

lar contact. This loop is partially enclosed in a tubular screen or shield of metallic material for electrostatically shielding the conductors thereof. One end of the loop is connected to the slip ring 5 6 and the other end is connected to the slip ring 7. The rings 6 and 7 are connected to one end of the inductance 8 and to the condensers 9, 10, 11, 12, and 13. The ring 6 is also grounded to the frame, chassis, or cabinet. The condenser 9 is 10 permanently connected across the loop 5, as shown, however, multiple contact switches 14 and 15 are employed to control the connections between the inductance 8, and the condensers 10, 11, 12, and 13, and the loop, whereby a plurality 15 of circuit combinations may be obtained between the loop, the inductance and the condensers for extending the tuning range thereof.

Taps of the inductance 8 are connected to different contact points of the switch 14 for the 20 purpose of enabling the operator to use all or only certain parts of this inductance at one time. A plurality of adjacent contacts of the switch 14 are connected together into a unit and this unit is connected to the variable condenser 25 19. Likewise a series of the contacts of the switch 15 are connected together, as shown, and this unit is connected to a similar unit of switch 14 which is connected to the condenser 10. Three contacts of switch 15 are connected 30 to the condensers 11, 12, and 13, respectively; these latter contacts correspond in position to the contacts of switch 14, which are connected to the condenser 10 and the contacts of switch 15 that are connected to the condenser 10 correspond 35 to the contacts of switch 14 that are connected to sections of the inductance 8. The switches 14 and 15 are mounted in tandem to be controlled by a single shaft, knob, handle pulley, gear or similar device, either manually or by some remote control mechanism.

Switches 23 and 24 are also mounted in tandem or in any other desirable manner to be controlled simultaneously as a unit for the purpose more fully described in the following paragraphs.

The antenna 16 is connected to the resistance 45 17, which is enclosed in the metal shield 18 together with the switch 19. The switch 19 is provided with a plurality of contacts, two of which are connected to the grounded end of resistance 50 17, one to the antenna end of the resistance 17 and one to a variable contact on said resistance. The contact arm of the switch 19 is connected to the grid electrode of the tube 4.

The plate electrodes of the tubes 3 and 4 are 55 connected together by a series of resistance units 20, 21, and 22. A condenser 25 is also connected between these plate electrodes. Multiple contact switch 23 is connected across the resistor 21 in such a manner that this switch short circuits 60 this resistor in three positions of the contact arm thereof. The switch 23 is arranged to be rotated in step with the switches 14, 15, and 24, and these switches are all illustrated with their contacts in proper relation with respect to the 65 contact arms thereof. Thus rotation of the common shaft of these switches establishes the proper circuit connections in these switches simultaneously. The switch 24 is employed to close the circuit between two contacts of the switch 30 70 to enable this switch to short circuit the cathode resistor 33 when the switch 29, which is mounted in tandem with the switches 19 and 30, is in the position designated D in Fig. 2.

The switch 30 is connected to the cathode of 5 the tube 4 to control the biasing potential of the

grid electrode of this tube with respect to the cathode. Two of the contacts of this switch are connected to the negative terminal of the plate power supply leads 38. The terminal R of switch 29 and the tube heater filament 36 are also connected to this negative power supply terminal as shown in Fig. 1 of the drawings. As described above two contacts of switch 30 are connected to the switch 24, one to the contact arm and one to a series of electrically connected contacts of this switch 24. Thus when the contacting arms of these switches are in positions shown in the drawings, they cooperate to short circuit the resistor 33.

Another resistor 32 is connected in series with the resistor 33 and this series is shunted by a fixed by-pass condenser 31. A similar series of resistors 27 and 28, shunted by a condenser 26 is connected to the cathode of tube 3. The contact arm of switch 29 and the end contact B are connected to the resistor 27 in such a way that this resistor is short-circuited when the switch arm of this switch is in contact with the terminal B.

Resistor 56 is connected in series with the positive power supply lead 38 to the resistances 21 and 22 connected between the plates of the tube. Another resistance 34 and fixed condenser 35 are connected to the resistances 21, 22, and 36 to form a shunt circuit between these resistances and the ground, which may be the metal cabinet, chassis and the like. Resistor 37 is connected in series with the filament 36 and the heating current power supply terminal 39; this resistor is also connected to the chassis as shown.

The output or plate circuits of the tubes 3 and 4 are coupled to the input circuit of the signal receiving apparatus 41 by the condenser 40 and the leads connected thereto, all of which are enclosed in suitable metal shields. The condenser 40 may be connected to the antenna binding post, connected to a radio frequency amplifier, of a conventional radio receiving set or it may be connected to the input circuit of the detector tube of a signal receiver. Where 45 desired, the tubes 3 and 4 may be selectively operated as detectors and the output thereof fed into an audio frequency amplifier through the condenser 40. In either case the telephone receivers 42 or similar translating or indicating devices are connected to be energized in accordance with signal energy.

The apparatus schematically illustrated in Fig. 1 is assembled into the cabinet, preferably of metallic material, such as, copper or aluminum, 55 shown in front vertical elevation in Fig. 2. The loop antenna container 5a is mounted on the top of the cabinet and is rotatable with respect to the cabinet. Any convenient form of mounting for the loop housing 5a, so that it may be 60 rotated with reference to the cabinet, may be employed. However, the mounting most readily adopted is a simple friction fit of the bottom tubular end of the loop housing into a hollow bearing formed in the top of the cabinet. The 65 circular scale-carrying member 43 is attached to the loop housing 5a and is rotatable with the loop. This circular member 43 may be employed to rotate the loop when such rotation is accomplished manually, and may be employed in conjunction with a suitable screw operated clamp 46, which is adjusted by the thumb screw 45, to lock the loop in place and prevent its rotation. This clamp 46 is particularly useful when it is desired to shift the scale mask 44 to a certain 70 75 position.

position for the purpose of covering a certain part of the scale.

An index or pointer 44a is attached to the cabinet 1 adjacent to the scale of the member 43. A hollow dome 47, also of metal, is removably held over a hole in the top of the cabinet to cover the top of the tubes to permit easy access thereto. Suitable spring and pin members 48 and 49 are attached to the cabinet and the dome 47, respectively, and cooperate together to hold the dome in place.

A control 50 is attached to the front of the cabinet and is connected to the contact arm 17a of the resistance 17 for the purpose of controlling the intensity or amplitude of the signal obtained from the antenna 16 when the switch 19 is in the position illustrated in Fig. 1, that is, the position corresponding to the position D of switch 29, which is connected in tandem with switch 19 and is operable by the knob 29a. A switch 51 preferably of the toggle type, is mounted on the front of the cabinet and is connected into the leads 38 as shown in Fig. 1. A plate 52 having inscribed thereon brief instructions for operation of the unit, is attached to the front of the cabinet.

The knob 14a is employed to control the position of the tandem mounted switches 14, 15, 23, and 24.

The knob 14a may be set in any one of seven positions, each of which corresponds to one of the contacts of each of the tandem switches that this knob controls. The primary purpose of this control is to select the signal frequencies to which the vacuum tube circuit is to respond and each setting of this knob is accordingly calibrated in accordance with a predetermined frequency band. The position occupied by the pointer of the knob 14a corresponds to the position of the contact arm of switch 14.

The dial 9a is used to control the position of the rotary plates of condensers 9 and 10. A locking clamp 9b is attached to the front of the cabinet and after the dial 9a and condensers are adjusted to the proper setting the thumb screw 9c may be tightened to clamp the dial in place to prevent further rotation thereof until the tension of the clamp is released.

A plug receiving socket 53 is attached to a side of the cabinet 1 for the purpose of facilitating making connections with an external power supply. A panel 54 of insulating material is supported inside of the socket 53 and connections 38 and 39 are supported on this panel. Binding post 16a is provided for connecting the antenna 16 to the unit and the coupling member 55 is employed to couple the unit to a shielded conductor connected to the conventional signal receiver input circuit.

The scale and scale mask carried by the stem of the loop antenna housing are illustrated in detail in Figs. 4, 5, 6, 7, 8, and 9 of the drawings. The dial 43 consists of a circular member fitted around the stem of the loop housing 5a in such a manner that the loop may be turned manually by engaging the periphery of the dial. The loop stem is provided on the inside with a suitable ceramic insulator 5b to space the loop conductors 5c. Arrows 43b are engraved on the top of the dial and point in a direction parallel to the plane of the loop.

Fig. 5 shows a bottom view of the scale dial 54 and mask 44. Mask 44 has a cut-away section 44b which extends over approximately half its circumference and when this cut-away por-

tion is over the front of the dial the scale 43a of the dial may be read from the front. When the zero mark 44c of the mask 44 (Fig. 9) is in line with the index pointer 44a (Fig. 2) the mask covers the front section of the scale. This cut-away section is shown in detail in Figs. 5, 7, and 8. Fig. 6 shows a section through the solid part of the mask ring.

The operation of the circuit arrangement and apparatus of my invention is as follows:

The selector 29a is set on the position R where-in in the loop tube section 3 is blocked through switch 29 applying proper bias to that section. Omnidirectional signal energy is then transferred from the non-directional antenna to the receiver 15 or amplifier 41 through tube section 4, antenna connection 16A, switch 19, condenser 40, and coupling connection 55.

The selector 29a is then set on position T, and while the frequency band selector 14a is on one 20 of the four positions adjusting the loop tuning circuit to one of the signal frequency channels between 500 and 8000 kilocycles, the tuning dial 9a is adjusted to tune in a continuous wave carrier, such as is transmitted by a broadcasting 25 station. In this position, switch 19 is connected to a contact that is grounded and the cathode of tube 4 is connected to the filament 36. This tube 4 is thus blocked and is unaffected by signal energy.

The dial 9a is next adjusted until maximum signal strength is obtained through tube 3, using the loop 5 as the signal pick-up. The loop is moved angularly, to the position of maximum signal intensity and acts in the conventional way 35 as a bilaterally selective pick-up.

The knob 29a is then turned to the position D. The loop is then rotated to determine whether or not signals of high intensity are received at one or two positions thereof. If two such positions are obtained, the loop is set in the position at which the weaker of the two high intensity signals is obtained and the control 50 for manipulating the contact 17a is operated until this weaker of the two high intensity signals 45 either disappears or becomes very weak. The loop is then rotated 180° more or less, to the other of the two high intensity signal positions and the signal receiving unit is operated as a uni-lateral receiver employing the loop and the 50 non-directional antenna in equalized and balanced relation.

If the antenna 16 is not of the correct proportions to enable the proper signal intensity balance to be obtained, as outlined above, condenser 20a connected into the circuit, is varied until the weaker of the two high intensity signals disappears. The signal pattern of the antenna system, including the loop and the antenna 16, is then cardioidal or substantially so.

The unit of my invention may be operated as a bi-lateral direction finder in the following manner: The knob 29a is set on position R and the receiver dial operated to tune the receiver to a station. Next this knob 29a is set on position 65 T and the loop is employed as a pick-up without the antenna 16. The loop is tuned by means of dial 9a and then the switch knob 29a is set on position D. The loop is then turned to the position giving the strongest signal and held in 70 this position by turning the thumb screw 45 of the lock clamp which engages a section of the dial 43 and prevents rotation thereof and the loop. The mask 44, which is carried by the dial 43, as shown in the detail views Figs. 5, 6, and 7, 75

and the exploded views Figs. 8 and 9, is rotated until the zero index reference 44c coincides with the index pointer 44a, mounted on the top of the cabinet.

5. The knob 29a is then set on position B, and the unit is operated as a bi-lateral directional receiver. The loop is then unlocked by manipulation of thumb screw 45 and swung to a minimum signal position with an unmasked portion of the dial over the index pointer 44a. The setting of the loop for minimum signal will give the bearing of the station, from which signal energy is being received, relative to the head of the ship, carrying the receiving apparatus of my invention.

13. There is another minimum signal position on the opposite side of the dial. However, this portion of the dial is covered by the mask and the taking of bearings on that portion is thus rendered impractical. The mask 44 is made with 10 the zero mark 44c and the cut-away section 44b arranged in such a way that after adjustment of mask 44 on the D position as described then the 15 unmasked section of the scale 43a is in view when the minimum signal is being received from a 20 transmitting station located in the direction of the head or front of the ship.

When it is desired to take very accurate bearings with the apparatus of my invention on an aeroplane, the loop should be adjusted so that a 25 signal dead ahead will have a zero signal at zero on the azimuth dial 43 and a correction curve 30 may be plotted to take care of deviations due to the influence of the plane structure. Should it 35 happen that the unit is not mounted exactly in the proper location and a signal from a station known to be dead ahead gives a bearing that reads some few degrees from zero the dial may be 40 readjusted to read zero by loosening the three screws 43c on the top of the dial to read zero by 45 moving the dial, until the reading is on zero while the loop is held in the position of minimum signal reception. The screws should be loosened only a very slight amount and carefully tightened after the dial is readjusted. A total motion of ten degrees in either direction is permitted by the mounting slots in the dial. If the error is more than ten degrees the entire unit must be 50 re-aligned with the center line of the plane.

In addition to the operation of the unit as a 55 fixed position for homing. For this purpose the procedure is the same as for the operation as a rotating loop except that the loop is locked with the dial at zero over the index pointer and the ship is swung instead of the loop. The 60 direction must be obtained on the D position and then the selector set to B when the pilot merely needs to keep the signal at the correct minimum to know that he is headed for the station.

65. In some cases, particularly at the higher frequencies it will be found that very accurate bearings may be obtained on the D position. In order to obtain the bearing relative to the plane heading when on the D position the mask is adjusted as described above and the bearing is read from the azimuth dial over the pointer on the right hand end of the unit. An even more rapid but less accurate method is merely to note the position of the arrows 43b engraved on the top of the 70 dial or, more easily still, note that the side of the loop painted in the lighter color always points toward the station when the loop is swung to the maximum signal on the D position.

75. For the taking of accurate bearings at high frequencies it is essential that the plane be at an

altitude sufficient that the curvature of the earth does not intervene between the plane and the transmitter. At a distance of 100 miles the plane must have approximately 9000 feet altitude in order to obtain good bearings. Useful directions on the D position may be obtained under average conditions at altitudes down to 5000 feet but on the B position the signal minimum is not clearly defined and tends to vary in apparent direction at altitudes less than 9000 feet. This example presupposes a comparatively flat terrain between the plane and the transmitter, such as over the sea. When mountains are between the plane and the transmitter greater altitude will be required.

Other methods of accomplishing the results set forth herein may be devised within the scope and spirit of this invention, and it is, therefore, not desired to limit this invention to the exact details set forth in the foregoing specification except insofar as these details may be defined by the appended claims.

This application is a division of my copending application Serial No. 31,084 filed July 12, 1935, for Radio apparatus.

What I claim and desire to secure by Letters Patent of the United States is as follows:

1. In direction finders the combination of a rotatable directional antenna, a substantially non-directional antenna and means connected to said directional antenna and said substantially non-directional antenna for obtaining bearings and direction with respect to predetermined transmitting stations, a scale-carrying member attached to said directional antenna and rotatable therewith, and a mask carried by said scale, said mask having a section thereof cut away to expose not more than half of said scale at one time, said mask being adjustable with respect to said scale to facilitate the use of different directional characteristics of said directional and substantially non-directional antennas in obtaining bearings and direction with respect to predetermined transmitting stations.

2. In direction finders, the combination of a 45 rotatable directional antenna having a metal casing, a substantially circular scale-carrying member attached to said casing, and a substantially circular ring-like mask having a cut away section to cover selected portion of said scale and fitted to said scale-carrying member and being slidable with respect thereto, said mask being rotatable with said member upon rotation of said directional antenna.

3. In direction finders, the combination of a 55 rotatable directional antenna, scale-carrying means connected thereto so as to be rotatable therewith, an adjustable masking means fitted over said scale-carrying means and having a section thereof cut away to expose not more than 60 half of said scale at any one time, said masking means being slidable with respect to said scale-carrying means.

4. In direction finders the combination of a 65 rotatable directional antenna having a metal casing, a substantially circular scale-carrying member attached to said casing for rotating said antenna, a substantially circular mask snugly fitted to said scale-carrying member, and being slidable with respect thereto for covering selected portions of said scale, said mask being rotatable with said member, and means for locking said scale-carrying member against rotation while said mask is rotated.

5. In direction finders the combination of a 75

5 rotatable loop antenna, a casing for said loop antenna, said casing having a mounting neck for supporting said antenna vertically, a cabinet for supporting said antenna, a scale-bearing member attached to said mounting neck for rotating said loop antenna, a rotatable mask snugly fitted to said scale-bearing member, said mask having a cut-away portion and being adjustable with respect to said scale for exposing only selected portions of said scale, and a lock for holding said loop antenna in a selected position while said mask is adjusted.

10 6. In direction finders employing a rotatable directional antenna, a substantially non-directional antenna, means connected to said directional antenna and said substantially non-directional antenna for employing said antennas selectively in obtaining bearings or direction and scale mask means for said rotatable antenna—the

15 20 25

method of obtaining bearings or determining direction including the following steps: receiving signal energy bi-laterally with said directional antenna, receiving signal energy uni-laterally with both the directional and the substantially non-directional antennas, rotating the directional antenna to determine the number of positions at which high intensity signal energy is received and adjusting the directional antenna to the position

at which the lowest of the high intensity signals is received, adjusting the signal output ratio between the antennas so that the lowest of the high intensity signals disappears or becomes very weak, rotating the directional antenna to the position of the highest intensity signal, rotating the mask means of the directional antenna scale means while the directional antenna is held stationary to mask the front part of the scale means, disconnecting the substantially non-directional antenna and rotating the directional antenna around until the back part or unmasked part of the scale is in view in the front to adjust the directional antenna in position so that it may be operated as a bi-lateral antenna on the minimum signal indication in the direction of the signal transmitter.

7. In a direction finder, the combination of a rotatable directional antenna having a rigid casing, a scale-carrying member attached thereto and rotatable therewith, a mask having a cut-away portion revealing a section of said scale carried by said member, said mask being slidably engaged by said member and rotatable therewith, and means for locking said member in any selected position.

CHARLES WM. HICKS.
